UNITED STATES PATENT OFFICE.

EDWIN W. RUSSEL, OF AYLESBURY, ENGLAND, ASSIGNOR TO CHARLES HARRY SENIOR,
OF AYLESBURY, ENGLAND.

FUEL-SUPPLY APPARATUS ON INTERNAL-COMBUSTION ENGINES.

Application filed July 14, 1921, Serial No. 484,752, and in Great Britain November 29, 1920.

This invention relates to fuel supply apparatus for internal combustion engines adapted to supply either of two fuels, for instance gasoline and paraffin, for the purpose of lessening the cost of running the engine by the use in part of the cheaper and less volatile fuel.

The object of the invention is not merely to enable the use of one or other of two fuels at will, but so far as possible to ensure the use of the cheaper fuel at appropriate times, while permitting such freedom of control to the driver as may be necessary to cope with exceptional conditions.

To this end there is combined with two carburettors connected by channels with the induction pipe of the engine a control device which varies simultaneously and oppositely the areas of the respective channels, and this control device is connected with the throttle valve of the engine, so that the driver on opening up the throttle will ordinarily also effect an appropriate change in the fuel in the sense of drawing to an increasing extent upon the cheaper and less volatile fuel, and to a decreasing extent upon the relatively costly gasoline.

It is a feature of the invention that the connection between the fuel control device and the engine throttle is a yielding connection. As a consequence of this the maximum adjustment of fuel, for instance complete change-over from gasoline to paraffin, may be effected short of full throttle opening.

A preferred embodiment of the fuel control device comprises a pipe having connections to the carburettors and between these connections a single connection to the engine, in combination with a piston movable in said pipe and connected with the throttle valve so that the two move together, the connection being adjustable, in order that the setting of the fuel control device for a given setting of the throttle valve may be such as is found to give the best results.

Inasmuch as the variations of fuel composition that are appropriate to the changes of throttle opening occurring in ordinary speed control during normal running, are not, or may not be, appropriate to the same changes of throttle opening during starting of the engine from cold, or in other special conditions, it is desirable, and it is a feature of the invention, to enable the driver to in-

terfere with the normal action of the control device on such special occasions. To this end an adjustable stop is provided under the control of the driver, which he can introduce into the path of the moving portion of the fuel control device so as to limit its action, the yielding connection to the throttle nevertheless permitting movement of the throttle to its full extent.

As the use of two different kinds of fuel complicates the problem of properly adjusting the composition of the mixture to the conditions under which the engine is running, the invention further contemplates an improved arrangement of throttle valve in the induction pipe of the engine in such manner as to control both the mixtures supplied and also the extra air admitted; and that the composition of the mixture may at all times be adjusted to what is found best, the invention provides means for readily determining the extent of opening to fuel admission which shall result from every setting of the throttle; and it also provides means for adjusting the extra air supply or substituting a diluent less rich in oxygen.

Further features of the invention will appear from the embodiments hereinafter described in detail, and are defined in the appended claims.

The invention is illustrated, largely in diagrammatic form, in the accompanying drawings:

Figure 1 is a diagrammatic showing of the means for ensuring complete vaporization, as well as of certain means for controlling the composition of the fuel mixture.

Figure 2 shows the combination of two carburettors with means for varying the supply taken from each according to the condition of the engine.

Figure 3 is an enlarged detail of Figure 2.

Figure 4 is an enlarged detail of Figure 1.

Figure 5 shows a modification of the construction of Figure 2, and

Figure 6 an alternative construction for the same purpose.

In Figure 1 an appropriate mixture of fuel and air formed in carburettng apparatus 1, 2, hereinafter described with respect to Figure 2, is admitted to a pipe 3. Preferably only so much air is admitted as is needed to carry over the requisite quantity of fuel. Pipe 3 is in part of its length

brought into thermal conductive relation with the exhaust gases of the engine, for instance, by being disposed in proximity to the exhaust pipe. In the construction shown 5 a part of pipe 3 is carried through an enlarged part 4 of the exhaust pipe. That the heat exchange between the fuel gases and the exhaust gases may be the more complete, suitable baffles may be provided which 10 ensure every part of the gases sweeping the wall through which the heat exchange occurs. For example, pipe 3, where it passes through the enlarged exhaust pipe, is shown as fitted with a number of cross bars 5, which 15 deflect the fuel gases in the middle of the pipe outwards against the wall of the pipe. The carburetting apparatus of the invention includes two carburettors supplied from two different reservoirs, one containing, say, gasoline and the other, say, paraffin. The parts 1, 2, of Figure 1 may be 20 taken as the float feed chambers of two such carburettors of which the jets 6, 7, are shown in Figure 2. These jets deliver into a common tube 8, which has a connection 9 to the fuel supply pipe 3 located between the two connections to the respective carburettors. In tube 8 is a piston 10 which is a 25 sliding fit in the tube and is adapted to move across the mouth of the connection 9. The piston is secured on a piston rod 11 carrying stops 12 which by their abutment on the closed ends of the tube limit the 30 movement of the piston. Outside the tube 35 8 a spring 13 surrounds the rod 11 and being compressed between the end of the tube and a cap 14 on the rod, presses the rod and therefore the piston towards an initial position in which the right hand stop 12 abuts 40 upon the end of the tube 8. In this position the piston 10 cuts off the fuel supply connection 9 from the paraffin carburettor jet 7, so that the whole fuel supply is taken from the gasoline carburettor. In the position of the 45 piston shown the supply is drawn substantially equally from the two carburettors; while by further movement to the left the piston can wholly cut off the gasoline supply when the engine is in a condition to 50 run on paraffin alone.

Figure 2 shows how the piston is adjusted simultaneously with the throttle valve. Loose upon the spindle 15 of the throttle valve there is a cam 16 having a projecting 55 crank arm 17. The spindle 15 bears also a cross-pin 18 which is joined by a spring 19 to the cam. As the throttle is opened by means of the crank arm 20 and inextensible wire 21 or other usual means the crank arm 60 18 bears upon the cap 14, and forces the piston towards the left against the action of the spring 13. When the piston reaches its extreme left-hand position further movement of the throttle merely extends the 65 spring 19.

To achieve the best results, means are provided to adjust the position of the piston for any given position of the throttle. As illustrated, the crank arm 18 has an adjustable extension 22 which forms the effective bearing surface of the crank upon the cap 14.

Upon freshly starting the engine, that is when it is cold, it may not be desirable to change wholly from gasoline to paraffin 75 until the engine has warmed up. For this reason a lever 23 is fitted, the end of which is in line with the path of the left-hand end of piston rod 11. The lever is controlled, say, from the dash-board of the car, for instance, by an inextensible cord 24. If the driver wishes to continue running on gasoline, or partly on gasoline, even when his throttle is wide open, he sets the lever 23 in the path of the piston rod so as to arrest its 80 movement at the desired stage, and lets it withdraw under the action of its spring when the engine is sufficiently hot for satisfactory running on paraffin.

It is preferred that the throttle shall control both the supply of combustible mixture to the engine and also the supply of extra air. For this purpose the throttle 29 of Figure 1 is shown located in a pipe 30 divided by a longitudinal partition 31, the axis 90 of the throttle being in the plane of the partition. The fuel supply pipe makes connection with one half of the pipe 30, while the other half is partially open to the atmosphere, the degree of opening being adjustable by a shutter 32. Preferably this shutter is hinged and pipe 30 is so placed that the shutter is closed when hanging substantially vertically downward. When the engine suction is sufficient the shutter is pulled open 100 by it to admit extra air; but if the engine speed drops the shutter closes so that the mixture is enriched in readiness for acceleration. Opposite the throttle valve 29 is a sleeve 33 making a sliding fit in pipe 30 and offering an hour-glass shaped channel for the passage of the gases. This sleeve is adjustable towards or from the throttle and is fastened in position by screw 34, which moves in a slot in pipe 30. The sleeve may 110 also be entirely removed and replaced by another of different interior shape. Preferably, as is seen in Figure 4, the form of the sleeve next the throttle differs little from the surface swept out by the edge of the throttle valve, so that a considerable movement of the throttle corresponds to a comparatively small change in the area of opening to the mixture, though the extra air admission may 120 be considerably increased.

Opposite the edge of the throttle valve when in its closed position a recess 35 is formed in the wall of the pipe 30, which can be filled more or less by the screw 36. This provides a by-pass of adjustable dimensions 130

for the passage of mixture when the throttle is in extreme position. A screw 37 may be employed to obstruct to a variable extent the path for the extra air. If this is used, the 5 sleeve 33 must be slotted as indicated at 38.

The oxygen content of the extra gas drawn in through the extra air passage may be reduced without reducing the volume of the gas, and with a gain in temperature, by connecting the exhaust pipe of the engine to the extra air conduit as shown at 39 (Figure 1), and providing a butterfly valve 40 in the connection. The valve may be connected with the throttle by means not shown so as 10 to be opened and closed with the throttle.

As a means of priming or flooding when the engine is to be started it is convenient to provide a connection from the gasoline carburettor 1 to the pipe 30 as indicated at 41, 15 controlling the connection by a cock 42.

Figure 5 shows a slight modification of the construction of Figure 2. A crank arm 51 upon a spindle 15 of the throttle serves to move piston 10 into position to close the 20 paraffin passage against the action of a spring 52; while the spring opens the paraffin passage and closes the gasoline passage so far as it is permitted by the opening of the throttle.

30 Instead of a sliding piston as 10, any other means may be adopted for changing over from gasoline to paraffin. In Figure 6 a hinged valve 53 can be rocked to close either the passage from the gasoline carburettor or 35 that from the paraffin carburettor. It may be operated by such methods as have been described with reference to the piston 10; for example, a lever 54 upon the valve spindle may be connected by an inextensible cord 40 55 to the throttle lever.

What I claim is:

1. In an internal combustion engine, the combination of two carburettors, a pipe into which both carburettors deliver, a single 45 outlet in said pipe between the connections to the carburettors, a piston fitting said pipe and movable across said outlet, an engine throttle valve, means connecting said piston with said throttle valve so that the two move together, and means for varying the setting of said piston for a given position of said throttle valve.

2. In an internal combustion engine the combination of two carburettors, a tube into which both carburettors deliver, an induction pipe connected to said tube between its connections to said carburettors, a piston fitting said tube and movable across the

mouth of the connection to the induction pipe, a piston rod secured to said piston, a 60 spring bearing on said piston rod to press the piston in one direction, a throttle valve in said induction pipe, a crank connected to move with said throttle valve and having its end bearing on said piston rod, and means 65 for varying the effective length of said crank.

3. In an internal combustion engine the combination of two carburettors, an induction pipe, channels connecting respective 70 carburettors with said induction pipe, a throttle valve in said induction pipe, means for varying simultaneously and inversely the areas of the channels from the carburettors, a yielding connection between said 75 means and said throttle valve, and a stop limiting the action of said means.

4. In an internal combustion engine the combination of two carburettors, an induction pipe, channels connecting respective carburettors with said induction pipe, control 80 means for simultaneously reducing the area of one of said channels and enlarging that of the other, a throttle valve in said induction pipe, a yielding connection between said 85 control means and said throttle valve, and an adjustable stop limiting movement of said control means.

5. In an internal combustion engine the combination of two carburettors, an induction pipe, a longitudinal partition dividing a part of said pipe, a throttle valve at the end of said partition having its axis in the plane of the partition, channels connecting said carburettors with one half of said 90 divided pipe, means controlling the relative area of said channels connected with said 95 throttle valve so as to be operated therewith, and means admitting air to the other half of said divided pipe.

6. In an internal combustion engine the combination of two carburettors, an induction pipe, a longitudinal partition dividing a part of said pipe, a throttle valve at the end of said partition having its axis in the plane of the partition, channels connecting said carburettors with one half of said 100 divided pipe, means controlling the relative area of said channels connected with said 105 throttle valve so as to be operated therewith, means admitting air to the other half of said divided pipe and an adjustable sleeve having a reduced passage through it adjacent to said throttle valve.

EDWIN W. RUSSEL.
